UNITED STATES PATENT OFFICE.

FRANK PAOLO GIANNANDREA, OF TOTTENVILLE, NEW YORK.

MUSICAL TOY.

1,189,092.

Specification of Letters Patent. Patented June 27, 1916.

Application filed November 12, 1915. Serial No. 61,199.

To all whom it may concern:

Be it known that I, FRANK PAOLO GIANNANDREA, a subject of the King of Italy, residing at Tottenville, in the county of Richmond and State of New York, have invented new and useful Improvements in Musical Toys, of which the following is a specification.

This invention relates to a musical toy of the inflatile type and preferably to a toy simulating a hunting horn and by means of which a prolonged musical sound may be produced varying in intensity and tone.

The primary object of the invention is to provide a toy of the class described having a fan disposed in advance of a sounding member and adapted to be rotated by a blast of air blown through the horn to cause the musical sound produced by the sounding member to be prolonged after the blast of air has been discontinued.

A still further object of the invention is to provide means which normally assists in maintaining the rotation of the fan after the blast of air through the horn has been discontinued and which will enable the fan to be rotated when the toy is held against the wind.

With these and other objects in view, the invention consists in the novel construction, combination and arrangement of parts which will be hereinafter described and pointed out in the appended claims.

The preferred embodiment of the invention has been illustrated in the accompanying drawing, although no restriction is necessarily made to the precise details of construction therein shown, as changes, alterations and modifications within the scope of the claims may be resorted to when so desired.

Like characters of reference denote corresponding parts throughout the several views in the drawing in which—

Figure 1 is a side elevation of a musical toy constructed in accordance with the invention. Fig. 2 is a vertical longitudinal sectional view. Fig. 3 is a vertical transverse sectional view on the line 3—3 of Fig. 2.

Referring to the drawing in detail, the numeral 1 designates the device as a whole which comprises a horn 2, having a fan casing disposed between the ends thereof and communicating with the interior of the horn, said fan casing 3 having a rotatable fan 4 located therein, and propellers 5 lo-

cated at opposite sides of the fan casing and rotatable with the fan 4. The fan casing 3 which is cylindrical in shape has extending transversely therethrough and projecting beyond the side walls 6 thereof, a shaft 7. The peripheral wall 8 of said fan casing is provided with spaced apertures 9 and 10. Extending radially from the peripheral surface 8 of the fan casing 3 is a tube 11 one end of which is disposed in the aperture 10 while the remaining end thereof is flared as indicated by the numeral 12. Frictionally maintained in the tube 11 adjacent the aperture 10 in the fan casing is a strip of material 13, the opposite ends of which are bent and rounded to contact with the inner wall of the tube 11 while the intermediate portion of the strip 13 is shaped to produce a whistling sound when a blast of air is passed through apertures 15 therein. Extending tangentially from the peripheral wall 8 of the fan casing 3 is a tube 16, one end of which is secured in the opening 9 while the remaining end of the tube is provided with a mouth piece 17, said tubes 16 and 11 cooperating to provide the horn portion of the device. The fan 4 which is disposed within the fan casing 3 and fixed to the shaft 7 has the blades thereof bent in such a manner that when a blast of air is directed into the fan casing 3, through the tube 16, the fan will be caused to rotate rapidly or slowly according to the velocity at which the wind passes through the fan casing.

It will of course be understood that when the fan is rotated, the propellers will also rotate and act similar to a fly wheel on a shaft and in this manner enable the fan to continue to rotate for a short time after the blast of air directed through the tube 16 has been discontinued. Thus it will be seen that when the fan is rapidly rotated either by air directed through the tube 16 or by the wind contacting with the propellers 5, the pitch of the tone produced by the air directed through the sounding member 15 of the fan will be regulated by the rapidity at which the fan revolves.

From the foregoing statement it will be at once apparent that a musical toy has been provided which will afford considerable amusement to children and also require a certain amount of skill to produce a continuous tone simulating a tune.

To prevent lateral movement of the shaft 7 in the side walls of the fan casing and to

enable the friction occasioned by the rotation of the shaft to be reduced to a minimum, the shaft 7 has secured thereto near each end thereof a ball 19 which contacts 5 with the side walls 6 of the fan casing 3.

From the foregoing description taken in connection with the accompanying drawing, it will be seen that a musical toy has been provided which may be operated in a manner similar to that used in blowing a horn 10 and also that a toy has been provided which is simple in construction, and inexpensive of manufacture.

Having thus described the invention, 15 what is claimed as new is:

1. A musical toy comprising a horn, a fan casing disposed between the ends thereof and having communication with the interior of the horn, a shaft extending 20 through said fan casing at right angles to the horn, a fan disposed within the fan casing and fixed to the shaft, a sounding member located in the horn and near said fan, and propellers fixed to said shaft exteriorly of the fan casing.

2. A musical toy comprising a horn, a movable sounding member disposed within the horn, a fan casing having communication with the interior of the horn adjacent

the sounding member, a shaft loosely 30 mounted in the side walls of the fan casing, means contacting with the side walls of the fan casing to prevent lateral movement of the shaft, a fan fixed to the shaft and having the blades thereof disposed in the path 35 of a blast of air directed through the horn, and a propeller on each end of the shaft exteriorly of the fan casing.

3. A musical toy comprising a horn having a fan casing communicating with the 40 interior of the horn, a shaft loosely mounted in the side walls of the fan casing and having the ends thereof extending beyond the same, a propeller fixed to each extending end of the shaft, a fan fixed to said shaft 45 and disposed for rotation in the path of a blast of air directed through the horn and fan casing to cause said propellers to revolve, and a sounding member disposed adjacent the path of movement of the blades 50 of said fan to receive the air therefrom.

In testimony whereof I affix my signature in presence of two witnesses.

FRANK PAOLO GIANNANDREA.
